US0D1036482S

(12) **United States Design Patent** (10) Patent No.: **US D1,036,482 S**
(45) Date of Patent: ** Jul. 23, 2024

(54) **DISPLAY SCREEN OR PORTION THEREOF
WITH GRAPHICAL USER INTERFACE**

(71) Applicant: **Lutron Technology Company LLC**,
Coopersburg, PA (US)

(72) Inventors: **Rhythm Agarwal**, Bethlehem, PA (US);
Benjamin F. Bard, Zionsville, PA (US); **Erica L. Clymer**, Northampton, PA (US); **Jemma C. Robinson**, Brooklyn, NY (US); **Sara M. Thompson**, Brooklyn, NY (US); **Shenchi Tian**, Easton, PA (US)

(73) Assignee: **Lutron Technology Company LLC**,
Coopersburg, PA (US)

(**) Term: **15 Years**

(21) Appl. No.: **29/778,704**

(22) Filed: **Apr. 14, 2021**

Related U.S. Application Data

(63) Continuation of application No. 29/689,303, filed on Apr. 29, 2019, now Pat. No. Des. 918,947, which is a continuation of application No. 29/612,902, filed on Aug. 4, 2017, now Pat. No. Des. 847,174.

(57) **CLAIM**

The ornamental design for a display screen or portion thereof with graphical user interface, as shown and described.

DESCRIPTION

The sole FIGURE shows a display screen or portion thereof with graphical user interface showing our new design. Shading represents tonal contrast.

The broken line showing of a display screen or portion thereof with graphical user interface is included for the purpose of illustrating portions of the article and forms no part of the claimed design.

1 Claim, 1 Drawing Sheet
